PROCESS OF MAKING SPLINTS

Alan E. Murray, New York, N. Y.

Application February 3, 1954, Serial No. 407,857

4 Claims. (Cl. 128—90)

My invention relates particularly to splints which may be applied over any desired portions of the body, such for instance as the arm, leg, neck, etc., to facilitate and correct the healing thereof, especially in the case where there are broken bones present, which require to be knitted together in the correct position.

An object of my invention is to provide more effective splints than were hitherto available, so as to eliminate the dangers that have occurred in the utilization of hard plaster of Paris splints of the usual type.

It has been found in practice that the usual plaster of Paris splints set very quickly and unevenly into a hard mass, which oftentimes has resulted in undue constriction of the arm or leg so that when left on the member until the healing has been completed a lack of circulation has resulted due to the uneven and unnatural binding by the plaster of Paris splint. In fact, malformations of the arm or leg have occurred therefrom which could not be thereafter corrected, so that the patient has at times been required to go through the remainder of his life with the resultant deformities.

It is one of the objects of my invention to avoid such disadvantages and dangers by providing splints involving the use of plastics, such for example as latex, etc.

As the latex herein referred to, I preferably use a latex which is a water-suspension of self-vulcanizing artificial rubber known as "neoprene," although latex made of natural rubber or any artificial rubber can be used herein. For the thickened latex herein I may use the "thickened latex" such as referred to in my Patent No. 2,568,291, which is made, as stated therein, by adding a thickener, such as methyl cellulose, to the self-vulcanizing water-suspended neoprene latex generally sold under the same name "latex."

The splints made in accordance with my invention are controllable over the entire area of the body portion, or member, under treatment and they permit the development, furthermore, of the dynamic natural position of the member throughout the treatment, by interpreting the position given to the arm or leg initially by the orthopedist in terms of the hydraulic technique demanded by the soft tissues which enclose the bones while being knitted or otherwise treated. In other words, although the member during treatment may be immobilized, nevertheless the splints made in accordance with my invention are much softer than any previous splints and more hydraulic in operation, and of such a character, furthermore, as to be capable of frequent replacement and such as not to set merely in spots before complete healing has taken place.

Further objects of my invention will appear from the detailed description of the same hereinafter.

While my invention is capable of embodiment in many different forms, for the purpose of illustration I have described and shown in the accompanying drawings only certain embodiments thereof, in which—

Fig. 1 shows a plan view of a patient in a reclining

2

position, having a splint, made in accordance with my invention, as applied to the right arm;

Fig. 2 is a cross-section of the said arm, showing applied thereto windings of felt and outside of the latter windings of monk's cloth;

Fig. 3 is a cross-section of the said arm showing the upper half of the said windings of felt and monk's cloth removed and substituted with an upper half of a plaster of Paris negative over the said arm with supporting loops 10 of string embedded therein;

Fig. 4 is an elevation showing the said upper half of plaster of Paris having the same supported from a neck-encircling strap;

Fig. 5 is a vertical section of a wall against which the 15 patient is leaning his head and upper half of the plaster of Paris negative illustrated in Figs. 3 and 4;

Fig. 6 is a cross-section of the said arm showing as applied thereto both the upper and lower halves of the plaster of Paris negative which form together a negative 20 cast;

Fig. 7 is a plan view of a positive master cast of plaster of Paris made in the said negative of Fig. 6;

Fig. 8 is a cross-section through the said master cast of Fig. 7, having applied thereon two halves of monk's 25 cloth as over-laid and enclosed with celastic;

Fig. 9 is a plan view of the resulting two halves of the 30 splint comprised of monk's cloth and celastic bound together at the joints of the two halves by lacings;

Fig. 10 is a side elevation view of a detail of the splint 35 shown in Fig. 9, but having a different mode of attachment of the two halves together, instead of by the lacings;

Fig. 11 is a cross-section of the positive plaster cast of the arm showing thereon the application of an alternative form of splint instead of the celastic splint shown in 35 Figs. 8 and 9;

Fig. 12 is a plan view of the splint shown in Fig. 11, having applied to the outside thereof longitudinal strengthening strips and transverse loops for attaching the halves thereof together with cotter pins, as well as supporting 40 straps with eyelets therein;

Fig. 13 is a plan view of a soft mobile splint made in accordance with my invention, for use during final convalescence;

Fig. 14 is an elevation in detail, showing another way 45 of attaching the two halves of the splint, of Fig. 13 for example, together;

Fig. 15 is a plan view showing the making of the splint in accordance with my invention, as applied to a leg;

Fig. 16 is a side elevation of a leg cast showing the 50 method of cutting the soft splint from the leg cast, in the making of a final splint of the entire leg and foot;

Fig. 17 is a front elevation of the splint being made for the neck of a patient; and

Fig. 18 is a transverse section showing a modified 55 mobile splint.

In carrying out my invention, it will be assumed that there is a broken right arm 1 to be set, and healed with the aid of the splints made in accordance with my invention. As soon as possible after the breakage has 60 occurred the orthopedist will set the position of the broken bones in the natural location of the bones before breakage. Thereupon, I provide a number of strips of felt 2, about $\frac{1}{4}$ " thick, obtained preferably as a split from felt $\frac{1}{2}$ " thick. The split of the desired thickness is 65 easily pulled off, but preferably in a tangential direction to the roll of felt, in the form in which it is produced on the market. The $\frac{1}{4}$ " thick felt thus obtained is found to be very soft and resembles in texture a series of layers of wool flock. These strips are preferably made

70 so that each is 2' or 3' long and 2" or 3" wide. It will be understood, of course, that instead of felt other similar fibrous material may be used.

The arm is then shaved to remove any hairs thereon and a little liquid skin lotion, such as a water suspension of waxy material used in making hand lotion, is then applied all over the arm, while the arm is being held in the desired natural position by the orthopedist. These strips of felt 2 are applied to the arm, one after another, after having previously dipped the strips to be applied in latex, from which the excess latex is wrung out by hand or in a wringer. Before each impregnated strip is applied to the arm it is laid flat on a support of any kind and powdered over the inner and outer surfaces thereof with powdered plaster of Paris.

The winding of each strip, thus prepared, is completed as quickly as possible so as to surround the entire arm, or at least the portion containing the broken bone, and the windings are thus built up into a crude thick wall made from the soft pieces of felt and preferably so as to make the wall thicker over the elbow or wherever desired to obtain additional strengthening by the felt. The impregnated felt, with or without the dusting of plaster of Paris, begins to contract immediately, even while putting it on the arm, due to the gelling of the latex. The felt itself is found to accelerate the gelling due to the pH character of the felt but it is found, also, that the plaster of Paris, if used, further facilitates and accelerates the gelling of the latex, which takes place by an even contraction all over the arm. This action is far superior to what occurs in the usual plaster of Paris cast made with cheesecloth, which becomes rock-like almost immediately, and which in practice is found to be unevenly hard in different spots, which quick uneven setting of the plaster impels the orthopedist generally unduly and incorrectly to manipulate the bone positions. On the contrary, in the splints thus made in accordance with my invention, the splints are yielding and subject to natural shaping under the influence of the soft tissues, so that the arm, or other portion of the body, has an opportunity to assume naturally the physiological contours due to the hydraulic character of the tissues enclosed. In other words, the reconstructive powers of the body are utilized to the maximum extent so that the arm acquires the natural conformation demanded by the body tissues.

I then apply to the outside of the felt, all over the arm, some of the latex, followed by powdered plaster of Paris. Next, I wind around, all over the felt, strips of monk's cloth 2a of the same dimensions as the felt strips 2, in order to seal the latex while wet within the felt. At the same time, or right after applying the monk's cloth strips 2a, I apply to the inner side of the monk's cloth 2a, while on the arm, a monk's cloth strap 3 which has been impregnated with latex, and dusted with plaster of Paris as in the case of the other monk's cloth 2a, which can be cut through by a split 4, thus producing two straps 5 and 6 which are provided with pairs of eyelets 7 and 8, as shown in Fig. 2.

An electric pad, or current of warm air from an electric hair-dryer fan, is then applied, at intervals, to the enclosing layers of felt 2 and monk's cloth 2a until the same are dry, which usually requires a period of about two days. This heating effect avoids lowering the patient's temperature due to the evaporation of the latex, which might otherwise tend to give the patient a cold, and has an advantage of lessening the pain of the healing.

Thereupon, after about three days following the applying of the felt 2 and monk's cloth 2a to the arm, two pencil lines 9 and 10 are applied longitudinally to the inner and outer faces of the monk's cloth enclosure and the said enclosure is then cut through the two layers 2 and 2a along the two pencil lines 9 and 10 with plaster shears, that is to say shears having the blades located at right angles to the handles of the shears. Now, the patient is made to lie down on his side, preferably, while an upper half 11 of the enclosure, comprised of layers

10

2 and 2a, is removed, thus leaving a lower half 12 resting on the body, supporting therein the arm. Then, I apply all around the upper edge of the lower enclosure 12 a flange 13 of plastelene, about $\frac{3}{4}$ " wide, which is a molding clay comprised of clay intermixed with a fatty or greasy material to prevent the clay from setting too soon. This is accomplished by squeezing the plastelene from a collapsible tube containing the same so as to make the flange 13 extend outwardly on the inner and outer faces of the arm throughout the length of the lower enclosure 12.

Then, I prepare a basin of plaster of Paris and cool water to a thick creamy consistency, having therein about a teaspoon full of salt to a 12" diameter basin $3\frac{1}{2}$ " deep, approximately filled with the said creamy plaster of Paris mixture. With a spoon or a spatula I now pour this plaster of Paris cream all over the upper face of the arm so as to form a thick negative plaster cast 14 extending upwardly from the said flange 13 on each side of the arm, as shown in Fig. 3. Before the plaster of Paris upper cast 14 hardens I embed therein a pair of string loops 15 and 16. This plaster sets, in about five minutes, into a hard rocklike mass, and then I introduce through the loops 15 and 16, as shown in Fig. 4, a neck-circumfering strap 17 having the usual buckle 18 so that the said strap 17 extends tautly, but not tightly, up and around the neck of the patient.

Now, the patient, as shown in Fig. 5, is made to stand, or sit up, so that his head and upper half of the negative plaster cast 14 rest against a wall 19. Thereupon, I take off the lower half 12 of the felt and monk's cloth enclosure and tear off the plastelene strips. It will be found that the upper half 14 of the plaster cast will now support the arm effectively, by means of the strap 17, by adhesion, etc. The lower edges of the upper half of the plaster cast 14 are now coated with a solution of sodium silicate of any desired consistency, that is to say soluble glass. Next, I apply to the under portion of the arm, in the place of the removed lower enclosure 12, a liquid comprised of plaster of Paris and water 20, of butter-like density, against the silicate of soda edges of the upper plaster cast 14. This plaster sets in about five minutes and the patient is then made to resume a reclining position. Now, the plaster is tapped lightly along the longitudinal meeting edges of the two negatives 14 and 20 with a mallet or small hammer and the two halves are separated, with the aid of a table knife to loosen the joints.

The top half 14 of the plaster negative cast is now removed after taking the strap 17 out of the loops 15 and 16, the lower half 20 being now supported by the body of the patient. Clean the exposed upper side of the arm with a little rubbing alcohol. Next, put onto the upper side of the arm the top half 11 of the soft felt and monk's cloth splint, resting the edges thereof against the lower plaster half 20 of the negative cast.

Again, the patient stands up and leans against the wall 19, as in Fig. 5. A string is then placed through the eyelets 7 and through the strap 17. Then the lower half 20 of the plaster cast negative is taken off and the lower soft splint 12 is slipped onto the underside of the arm, and adhesive tape is now wound around the felt negative splint with about six windings or more on every portion of the arm, to hold the two halves together. Then the same string is passed, also, through the eyelets 8 and through the strap 17. Strong elastic rubber bands are now placed over the two halves to keep them together before making the positive plaster cast.

To complete a negative cast the two plaster halves 14 and 20 are now placed together, with their edges fitting together, after applying a silicate of sodium solution thereto on their inner faces, throughout the interior of the negative cast.

This provides a negative master cast of plaster from which a positive cast can be made by closing off the

lower end of the negative 14, 20, with a thick plaster of Paris and water mixture which is allowed to set.

Now, a creamy plaster of Paris and water mixture is poured into the top of the negative cast 14, 20 while vibrating the same slightly with a little jarring. This is allowed to stand for about one hour to completely set. When the two plaster halves 14, 20 are removed, this leaves a plaster of Paris positive 22, from which to make any number of desired splints having the true conformation, with the correct reproduction of the shape of the physiological arm, in the correct position of choice determined by the orthopedist, and which may be light and elastic. This light perfected splint 23, in two halves 24 and 25, can be made by putting on the positive cast 22 a top L-shaped monk's cloth 26, after coating the cast 22 with some of the thickened latex while turning up at the inner and outer sides of the arm $\frac{1}{2}$ " side flanges 27 and 28 all around the parting lines, corresponding in position to the lines 9 and 10. Then turn the cast over 22 and put a second piece of monk's cloth 29 over the remaining side of the cast 22 with flanges 30 and 31 thereon, proceeding as in the case of the monk's cloth 26.

Then, after placing the cast 22 in the original position, I provide a sheet of celastic material 32. This material is a heterogeneous mixture of nitrocellulose, that is to say pyroxylin and camphor, carried in a sheet of loose weave cotton pile fabric, although the camphor may be omitted. It has the appearance of blotting paper before having the solvent applied thereto. The celastic material is applied (using rubber gloves, preferably) by first softening it in a liquid solvent which is non-water-miscible ketone or ester such as methyl ethyl ketone or ethyl acetate or a mixture of solvents such as methyl alcohol and ether, so that when the solvent liquid evaporates there is left an elastic form-retaining shell similar to Celluloid. Any other elastic plastic material which can be softened by solvents leaving a stiff hard form-retaining shell by the evaporation or elimination of the solvent liquid, could be used. The sheet of softened celastic material 32 is worked in with the fingers over the monk's cloth 26, providing flanges 33 and 34 thereon, as shown in Fig. 8. Then turn the cast 22 over and apply thereon, similarly, a celastic sheet 35 with flanges 36 and 37. Now, after cutting the two halves 32 and 35 apart with a razor between the flanges longitudinally on the inner and outer sides of the cast 22, holes 38 can be made through all these flanges, as in Fig. 9, and lacings 39 and 40 can be passed through the holes to bind the two celastic halves 32 and 35 together, when placed on the arm of the patient during convalescence.

As an alternative form of fastening, however, I may, as shown in Fig. 10, cut off all the said flanges shown in Fig. 8 and while the celastic 32 and 35 is still soft from the presence of the solvent, I can apply to the celastic margins 32 and 35, respectively, on the inner and outer faces of the arm cast 22, a series of celastic strip loops 41 and 42, which have looped ends passed over a series of cotter pins 43 that can be removed and replaced when removing the hard dry celastic shell 32, 35 from the positive cast 22 and then applying the celastic shell to the arm of the patient during convalescence. Perforated supporting straps 43a, of celastic, over any selected loops 41 and 43, may be similarly applied to the upper and lower celastic halves 32 and 35.

This technique, thus, provides first the two felt halves 11 and 12 as a positioner and thereafter a top or first plaster half 14 of the negative cast which acts as a baffle, while the lower half 20 of the plaster negative applies the correct physiological shape of the arm hydraulically against the baffle 14 in the process of forming the splint. The felt positioner 11, 12 provides the correct position and the plaster preserves the correct hydraulic conformation of the tissues of the body mem-

ber, without the distortion previously produced by the uncontrollable, uneven, quick rock-like hardening of the usual plaster splints, for making final rigid or elastic or semi-flexible or soft splints therefrom.

- 5 An alternative mode of procedure in making the final splint, and especially where it is desired to provide a softer and more flexible final splint, to be used instead of the celastic splint of Figs. 8 and 9, is shown in Figs. 11 and 12. In accordance with this procedure, I apply latex all over the positive cast 22. Then I provide a sheet of felt 44, about $\frac{1}{2}$ " thick, similar in character to that above referred to, having in general the L-shape of the upper face of the positive cast 22 so as to be wide enough to cover the entire upper or outside half of the cast 22 and so as to produce horizontal flanges 45 and 46 all around the inner and outer meeting edges of this felt 44, adjacent to a similar lower felt 47 to be applied later to the underside of the arm, with like flanges 48 and 49. Before being applied over the cast 22, the upper felt 44 is powdered on the inner face with plaster of Paris and the upper or outside side of the said felt 44 is then coated with Duco cement, which is a cellulose acetate dissolved in any suitable volatile solvent. This cement may be applied to the outer face of the felt 44 before or after being applied to the positive cast 22. Two other pieces of felt of the same character, shape and size 50 and 51 are then each coated on the outside with Duco cement in the same manner and successively applied over the top of the felt layer 44. Then, in a similar manner, three similar layers of felt 47, 52 and 53 are applied to the underside of the arm with similar flanges in each of the six layers, each of the said felts 44, 50, 51, 47, 52 and 53 being provided with flanges, as above referred to, around the meeting edges on the inner and outer sides of the cast 22. If desired, there can be applied a fourth felt layer 55, to decrease thermoeconductivity, in two halves and in the same manner respectively above and below the cast 22. Also, if desired, there may be applied upper longitudinal reinforcing strips of felt 56 and 57 in a similar manner to the upper half and similar strips of felt 58 and 59 on the underside. Now, a razor blade cut is made between the edges of the inner side of the cast, as well as on the outer side of the cast, after having cut off the protruding flanges of the felt layers on the inside of the cast as well as the outer side thereof. Any number of short fastening straps 60 may be applied to the inner and outside edges of the upper half thereof, each of which is provided with a loop 61 protruding over the meeting edge of the lower half thereof, and similarly looped straps 62 may be applied over the lower half. All of these straps are fastened to the adjacent felt layers 51 and 53 or the felt layers 54 and 55 with the same technique as used in applying the succession of felt layers to the cast 22. However, it will be noted that the loops 61 are placed so as to be laterally adjacent to the loops 62 so as to permit the insertion of cotter pins 63 in the adjoining loops 61 and 62 along the inner meeting edges of the two halves.
- 60 Instead of these last mentioned splints shown in Figs. 11 and 12, which are also somewhat rigid, in a way similar to the splints of Figs. 8 and 9, I may provide a mobile splint, to be used during the final convalescence of the patient, as shown for instance in Fig. 13. This is 65 a semi-elastic splint which can have varying degrees of elasticity, according to its thickness etc., which is particularly useful in the final healing of the member where some portions of the splints may be located opposite to bone ends that are chafed or sore, due to the thinness of the tissues. For this purpose I may, for instance, add a slight additional layer, about $\frac{1}{16}$ " thick, of plaster of Paris 64, and water, at the elbow of the cast 22, or at 70 any other point where pressure is to be avoided on a chafed or sore portion of the body, thus producing a modified positive cast 65. On this cast 65 the elastic

splint may then be made from $\frac{1}{32}$ " thick felt 66, in the same manner as described in connection with Figs. 11 and 12 but by using, in this instance, the thickened form of latex on the felt 66, but with the same technique as just described previously. Thereupon, I apply above and below the cast 65 on the upper and lower felts 66 thicker L-shaped pieces of felt 67, about $\frac{1}{4}$ " thick, which can be of a cheaper grade of felt, which is usually dark grey. For applying the pieces of felt 67 above and below the cast, the said layers 67 are first dipped in latex and wrung out to remove the excess of the latex. Also, before these layers 67 are applied the thinner felt layers 66 are brushed with thickened latex. Before applying the layers 67, furthermore, the latter may be powdered on the inner faces with plaster of Paris just after being dipped in the latex and wrung out. They are then immediately pressed down onto the thin felt layers 66. It will be understood that these layers 66 and 67 are all provided with the flanged edges in applying the same over the positive cast at the lines where the upper and lower halves of the felts meet along the inner and outer faces of the cast 65.

Then, longitudinal reinforcing strips 68 and 69 may be applied to the top and bottom felts 67, as in the case of the felt laminations coated with the said Duco cement. Perforations 70 can be made at intervals, in the strips 68 and 69 and through the layers 66 and 67, after cutting off the inner and outer flanges on said felts and severing the two splint halves, along the inner and outer sides of the splint, with a razor blade, and removing them from the positive cast 65. However, instead of the thick felts 67 there may be applied pieces of celastic $\frac{3}{32}$ " thick, with the aid of the solvent technique previously described, which may be fastened together as shown in Figs. 9 or 10.

It will be understood that any of the reinforcing strips 56, 57, 68 and 69 can be omitted, if desired, to make the splint more flexible. Also, in this construction, instead of using cotter pins for fastening the edges together, as shown in Fig. 10, I can fasten the meeting edges of the two splint halves by having near each of the four edges shoe-eyelet hooks 71 and short rubber bands 72 thereon, to be stretched onto the opposing shoe-eyelet hooks 71 to releasably fasten the same together. This enables the tightness of the splint to be readily controlled by selecting rubber bands 72 of the desired length and thickness, and which may be very thin during final convalescence. The avoidance of pressure can be aided by eliminating some of the rubber bands 72 when desired. This, furthermore, permits and preserves the dynamic use of the arm by partially opening the joints of the splints during convalescence, to improve the circulation of the blood and bring about better contact of the skin with the air, thus facilitating the healing action.

If it happens that the arm or other member of the body shrinks while healing, so that the splint becomes too loose, this can be offset to the desired extent by applying to the inner faces of the splint halves one or more layers of terry cloth 73 and 74 having Duco applied to the outer faces thereof, as indicated by dotted lines in Fig. 11.

As above indicated, any other members or parts of the body can be provided with splints in substantially the same manner.

For example, as shown in Fig. 15, if a leg 75 has been broken and is to be provided with a splint, this can be done in any of the ways hereinabove described, as for instance involving the making of initial wrappings 76 of felt and monk's cloth, which may be cut apart with shears along a longitudinal top median line 77 and along a corresponding median line on the underside of the leg, by first having the patient lie on his back and thereafter on his face and then making the subsequent negative and positive plaster cast and rigid or elastic or semi-

flexible or soft splints therefrom, as hereinabove set forth. This will generally be done by not including the entire leg and foot in a single splint. Also, in making the splint for the leg, it will of course be understood that the same may be made when necessary without rolling the patient over from one side to the other, by first making the half of the splint on the upper side of the leg with the patient lying on his back and thereafter proceeding as described above for making the splint for the underside of the leg while the leg is elevated sufficiently for this purpose.

Another way of producing the splint for the leg, and in which the splint can be used as an ambulatory cast, in which the cast or splint can be walked on, would be as follows: As shown in Fig. 16, the splint may be made for a leg, which includes not only the leg itself but also the foot. This may be found desirable because of the extent of the fracture or damage present in the leg or owing to the pathological condition of the veins or tissues. In making the splint in this way, the patient will preferably be lying on his back and the splint 78 of felt and monk's cloth will be made as above described, but by enclosing both the leg and the foot. Then, the splint 78 is cut with the shears along a line 79 extending longitudinally along the side of the leg over the ankle, then forwardly around the foot to approximately the upper ends of the toes and thence rearwardly along the foot and longitudinally along the other side of the leg, in a direction corresponding to the line 79, as shown in Fig. 16. Then the negative cast, positive cast and rigid or flexible or semi-flexible or soft splints can be made therefrom in accordance with any of the procedures previously described. This can be facilitated by rolling the patient over from his back to his face position or vice versa, when desired, or the operations can be conducted, instead, by lifting the leg from time to time, as above referred to.

In the case of varicose veins and similar pathological conditions in the leg or elsewhere, splints may be advantageously made in the above manner and applied on the leg, for instance as above referred to. However, a splint for this purpose may be made instead from a stocking of any desired fibrous material, which is placed on the positive cast of the leg. Then the stocking is painted all over with latex, which is allowed to dry for two or three hours. After this, a razor blade is used to cut down the two sides of the cast longitudinally, followed by taking off carefully the two sections of the stocking with the set latex therein. These two halves are then put together by fastening zippers to the longitudinal edges on both sides of the splint, or by means of fastenings made with hook-eyelets, as above referred to, or even with snap fasteners. The splint thus made can be applied to and taken off the leg in halves repeatedly at intervals for treatment of the leg, ventilation, washing, etc.

Also, as another example of a member or portion of the body for which the splints may be made, in case of a broken neck or paralysis or weakness of the neck muscles which require assistance, splints therefor may be made in a similar manner.

Accordingly, in making a neck splint the neck 80 is wrapped around under the chin carefully and softly with the impregnated felt strips 2, with or without overlying strips of monk's cloth, flanging out, as shown in Fig. 17, until they overlie the shoulders of the patient, following the technique described in connection with Figs. 1 and 2. Thereupon, with the shears, cuts 81 and 82 are made along the tops of the shoulders laterally of the patient. Then the patient is placed on his back and a front half 83 is lifted off and, following the technique described in connection with Figs. 1 and 2, a plaster half of a negative cast is made in the place of the half 83 which has been removed. After this, the patient is turned on his face and a back half 84 is

removed and a back half of the negative plaster cast is made in the place thereof, again following said technique of Figs. 1 and 2. The patient is put on his back again and the half of the felt splint 83 is restored in place of the plaster negative half and thereafter the same procedure is followed by turning the patient on his face and applying the rear felt half splint in place of the rear negative cast. After this, the two negative plaster halves are fastened together by windings of tape, the narrow or neck end of the resulting negative is closed with a dam of thick plaster of Paris and water mixture, and after coating the inside of the negative with silicate of soda solution in water, a positive plaster cast is made by pouring a thin mixture of plaster of Paris and water into the negative cast. When this positive cast has set it is removed and can be used for making thereon any of the previously described rigid or semi-rigid, elastic or semi-flexible, or soft splints to be placed around the neck of the patient and removed as often as necessary so as to facilitate the treatment, recovery and convalescence of the patient. In this way, the muscles of the neck can be restored gradually and completely to their original functions, as the supporting splints, especially when applied to the neck in the form of splints of increasing thinness and flexibility and decreasing rigidity, can effectively aid the restoring of the original strength and functions of the muscles of the neck and shoulders.

As shown in Fig. 18, I may provide a semi-flexible very light splint for final convalescence, for any member of the body, for example the arm, which is made over the positive cast thereof. This splint is made of three thin layers of $\frac{1}{32}$ " thick felt in six halves or pieces 85, 86, 87, 88, 89 and 90, so that the pieces 88, 89 and 90 overlap the lower sides of the pieces 85, 86 and 87, instead of the free lower edges previously referred to, but having open upper edges ending in flanges 91, 92, 93, 94, 95 and 96, provided with transverse holes 97 and 98 for eyelets and lacings. Series of lines of transverse ventilating holes 99, 100 and 101, arranged longitudinally of the splint 102 thus produced, may be provided, if desired. This splint may be made of the three felt layers above referred to, secured together by any of the above techniques. However, for this purpose, thickened latex may first be applied to the positive cast, after which each of the felt layers 85, 88, 86, 89, 87 and 90 is applied thereto in succession after having dipped it in thickened latex and wringing it out. After these felt layers are applied, they can be allowed to dry for about twelve hours, and are then brushed with a power-driven rotary brush to remove any loose nap.

Also, if desired, any of the final splints hereinabove described, if they are to be worn for a long time, can be covered with leather, such as a soft kid, by applying the same, according to the leather technique of my Patent No. 2,493,310, granted January 3, 1950, in pieces or halves corresponding in shape and size to the pieces of fabric that have already been incorporated in the particular splint.

The modulating healing effect of the splints during the recovery of the patient will be found to be especially advantageous in the treatment of polio, in which the maximum possible activity or use of the muscles is desirable to be brought about during convalescence. In other words, the decrease of the degree of support with the increasing recovery of the patient is of paramount importance.

Many other parts of the body can be provided with splints in this manner, as for example, the hips, shoulders, etc.

While I have described my invention above in detail I wish it to be understood that many changes may be made therein without departing from the spirit of the same as defined in the claims.

I claim:

1. The process of making splints having a permanent impression of a body member therein which comprises the steps of applying fabric material impregnated with liquid rubber latex in uncured form to a body member to form a soft yielding fabric cast which readily conforms to change in the shape of the body member while the liquid rubber latex cures, maintaining the cast on the body member until the uncured liquid rubber latex is cured to the extent that a permanent impression of the body member is formed therein, cutting said fabric cast longitudinally into two separable portions, removing one of said portions, forming a first partial negative plaster of Paris cast on the body member in place of said removed portion while the body member is supported in the second portion of said fabric cast which serves as a lock that tends to prevent distortion of the fleshy portion of the body member while the partial negative plaster of Paris cast is being formed on said body member, removing the second portion of the fabric cast, forming a second partial negative plaster of Paris cast on the body member in place of the removed portion of the fabric cast to form a complete negative plaster of Paris cast on the body member, removing said negative plaster cast, forming a positive plaster of Paris cast in said negative plaster cast, removing the positive plaster cast from the negative cast and then molding a negative cast of plastic and fabric material on said positive plaster cast to form a splint which contains a permanent impression of the body member therein adapted to fit the contours of the body member.

40 2. The process specified in claim 1 which includes the steps of cutting the fabric cast into a plurality of separable portions, removing consecutive portions of said fabric cast and forming in succession a substitute negative plaster of Paris cast on the body member in place thereof.

45 3. The process specified in claim 1 which includes the step of supporting the body member in said first partial plaster of Paris cast while the second plaster of Paris cast is being formed on said body member.

50 4. The process described in claim 1 which includes the step of dusting the liquid rubber latex with plaster of Paris to accelerate the setting and curing of the rubber latex.
